UNITED STATES PATENT OFFICE.

THEODORE C. STEIMER, DECEASED, LATE OF PITTSBURGH, PENNSYLVANIA, BY
CHARLES M. STEIMER, ADMINISTRATOR, OF PITTSBURGH, PENNSYLVANIA;
SAID THEODORE C. STEIMER ASSIGNOR TO EMPIRE MACHINE COMPANY, A
CORPORATION OF MAINE.

GLASS-HANDLING APPARATUS.

1,362,756.

Specification of Letters Patent. Patented Dec. 21, 1920.

Original application filed February 12, 1910, Serial No. 543,582. Divided and this application filed March 26, 1920. Serial No. 369,078.

To all whom it may concern:

Be it known that THEODORE C. STEIMER, deceased, a citizen of the United States of America, who resided in the city of Pittsburgh, county of Allegheny, and State of Pennsylvania, did during his lifetime invent certain new and useful Improvements in Glass-Handling Apparatus, of which the following is a specification.

This application, which is a division of a prior application filed Feb. 12, 1910, Serial No. 543,582, has for its object to claim a mechanism shown and described therein, and embodied in a machine adapted for the glazing or fire-polishing of glass-ware. This machine, generally speaking, comprises a constantly revolving frame, a furnace with properly heated openings, and glass-handling devices for presenting the glass articles to the furnace openings, both mounted on and moving with the frame, and transfer devices for receiving the articles from a fixed delivery station, and for positioning them where they may be taken up by the glass-handling devices, and for taking them from such devices and delivering them to a fixed receiving station. The transfer mechanisms, which *per se*, constitute an important feature of this invention, both move with, and move relatively to the revolving frame, and so may be held stationary at times. During the latter period, they are successively in registration with one of the fixed stations. During the period during which they move with the frame, they are in such co-operative position with the glass-supporting mechanisms as to deliver to the latter, or to receive therefrom, the article under treatment, while the motion of the transfer devices in respect to the traveling frame restores such transfer mechanisms to the angular position which they occupied on the frame prior to the stoppage of their motion in respect thereto.

A further feature of this invention is the use of associated pairs of parts, one of which parts is loaded on passing the loading station and from which the glass is transferred to the other part before the completion of a revolution of the parts, whereby such first loaded part is emptied to receive a new load

before it again passes the loading station. The article transferred from the first part is carried past the loading station on the other part, and is then discharged. This overlap 55 prolongs the period in which the articles can be retained in the machine without reducing the capacity thereof due to slowing down its cycle. This feature of my invention is independent of the stoppage of the parts at 60 the stations for loading or unloading.

The invention further consists in the construction, arrangement, and combination of the several parts of which it is composed, as will be hereinafter more fully described 65 and claimed.

Referring to the accompanying drawings, in which corresponding parts are designated by corresponding marks of reference,

Figure 1 is a vertical central section taken 70 on line 1—1 of Fig. 4 of a fire-polishing device embodying this invention.

Fig. 2 is a partial section and plan on the line 2—2 of Fig. 1, showing the means for operating the holder carrying the article 75 during the fire polishing.

Fig. 3 is a partial front elevation of the lifting device and shaper for the glass articles seen at the right of Fig. 1.

Fig. 4 is a plan view of the table of Fig. 80 1, and a section on line 4—4 thereof.

Fig. 5 is a side elevation showing in detail, the transporting or take-off devices, appearing in plan at the left of Fig. 4.

The invention in the embodiment here 85 shown, includes a fire-polishing furnace (which may be of a known construction), and glass-handling devices for placing and holding the glass articles in, or opposite to the glory holes 113 thereof, all mounted for 90 continuous rotation around a central vertical axis on a table 115.

On the frame or standard 114, I mount a table 115 which is continuously rotated by a bevel gear 116 and a pinion 117 on shaft 95 118 which by gears 119 and shaft 120 is connected in any convenient way with a main power shaft. The fire is furnished by a burner 121 in the center of the frame 114, entering the throat 122 of the furnace 112, and this latter is supported on the rotating table 115 as hereafter described. An exten-

sion 123 of the frame 114, carrying a fixed cylinder 124, supports fixed cam plates 125, 126 and 127. All the other parts of the machine revolve. The revolving table 115 is provided around its outer edges with studs 128 supporting a plate 129 which in turn carries a series of stationary blocks 143 and stanchions 150 supporting plate 151, and the latter in turn carries supports 152 for the furnace 112.

Between two dependent lugs 153 fixed on the plate 151, I provide a series of lifters shown in front elevation in Fig. 3. Each consists of a lifting device or box 131 pivoted on pins 132 and containing a series of rollers 133 mounted therein in inclined semi-circular arrangement and driven through intermeshed gears 134 by a system of gearing 135 driven from shaft 136 which in turn is rotated by the rack 137 fixed on an extension 138 of the fixed frame 114.

At points spaced around the axis about which the furnace revolves is a delivery table 110, and a receiving table 168, while carried at the periphery of the revolving base plate 115 are a series of article supports 111 and 160, each capable of being respectively brought to rest opposite and adjacent to the respective tables in their passage thereby, and having for this purpose a limited circumferential movement in respect to the base plate. A glass article, shown in the drawing as a tumbler T, can be shoved either by hand or by appropriate timed mechanism 35 from off the delivery table to the support 111 opposite that table, or can be pulled off the support 160 opposite the receiving table onto that table.

It will be seen from Fig. 1 that when the box 131 hangs vertically down from its pivots 132, it stands behind the tumbler T on the rest 111. By means of a rack 140 in the plate 129, engaging a gear 141 on the pivots 132, the box is swung up to the horizontal position shown in dotted lines in Fig. 1, in which motion it passes around the rest 111 and receives the tumbler T, (as will be plain from Fig. 1) and carries it up in line with a holder 142. This motion of the rack 140 is imparted by the engagement of a depending stud roller 140^a engaging the cam slot 127^a in the fixed plate 127. A plan view of this rack 140 in the plate 129 is shown in Fig. 2.

Placed parallel with each rack 140 and to the plane of movements of its lifting box 131, there are fixed blocks 143, in which is guided an oscillating block 144 pivoted on a trunnion 144^a in a pair of the stanchions 150. This block 144 has a forwardly extending tubular arm 146 in which is mounted the stem of the holder plug 142, and the back end of this stem 146^a engages a sliding block 147 movable in ways in block 143 and reciprocated 60 by the engagement of the pin extensions 148^a

on arm 148. The arm 148 is pivoted on the next block 143 and it has a roller stud 149 which engages a cam slot in the fixed plate 126, above, as will be evident from Fig. 1. This shoves the stem 146^a and its holder plug 70 into the tumbler when it is in horizontal position, and then, by the engagement of a gear 154 on the shaft 144^a with a reciprocating rack 155 set in the plate 151, the tumbler is swung up into vertical position within the 75 glory hole 113, as indicated in dotted lines at the left of Fig. 1. The rack 155 is moved by the engagement of roller stud 156 with a cam slot in the fixed plate 125. Meantime, the arm 146 of the holder plug is rotated by 80 a pinion 145 engaging an idler 145^a surrounding the trunnion 144^a and driven by a pinion 157 on shaft 158, which in turn is driven by means of rack 159 also fixedly mounted on the base extension 138 which 85 carries the rack 137.

While the tumbler is in the fire of the glory hole, it will be observed that the edge of the tumbler next the fire is in a vertical position to avoid any distortion, and that 90 it is rotated so that it is heated evenly all over. By the time the machine is rotated another 120 degrees or any other desired distance, the cam slots reverse the motions just described; the supporting arm 146 lowers 95 to a horizontal position and deposits the tumbler again in the revolving rollers 133 of the lifting box 131, and eventually this returns to vertical position leaving the tumbler on the rest 160 as shown at the left 100 of Fig. 1. The tumbler in handling has been constantly operated on to keep it moving and maintain its shape, it being understood that the rollers 133 will in each case be made to exactly fit the sides of the article 105 being made. The tumbler is now finished and is carried into the leer as hereinafter explained.

Coming now to the horizontal movements of the supports for the tumbler; it will be 110 seen from Figs. 1 and 4 that these supports 111 and 160 are carried on sliding blocks or partial ring sections 161 which are set on the revolving table 115 and are free to move. Referring to Fig. 4, especially, these tumbler 115 supports are arranged in pairs, there being one of each kind on each of the blocks or partial rings 161. It is necessary not only to bring them into register with the table 110 intermittently, and leave them stationary for a moment, but also necessary to alternate their position under the lifting devices 131 and 142, which are continuously moving around the machine. For this purpose I mount upon the traveling table 115 a 120 series of transporting arms 162 pivoted at 163 and by means of a slot 164 engaging a pin on the sliding block 161. The end 165 of each arm 162 projects beyond the circumference of the table 115 and as it arrives 130

near the position of table 110, so that the support 160 is in position to receive the tumbler, it strikes a stationary lug 166 which prevents its further motion until the 5 tumbler has been put in place and the end 165 slides past the fixed lug 166. When this escapement happens, the block 161 is again carried along with the table 115 so that the tumbler support 111 is in register with the 10 lifting devices as before described. While the tumbler is being transported and treated in the glory hole, the receiving holder 160 is brought into register with the lifting devices, by the striking of the arm 162 on one of 15 the fixed lugs 167 seen in Fig. 4, so as to cause the receiving holder 160 to take the relative position formerly occupied by the holder 111.

The operation of fire-polishing having 20 been completed, the tumbler is returned to original position and at such time it is placed upon the holder 160. This does not occur until the table 115 has made five-sixths of a revolution; that is, after the arm 162 25 has struck the second lug 167 shown at the bottom of Fig. 4, so that the tumbler after being finished has been carried from about the position marked X in Fig. 4 to the delivery point at the left of the figure. But 30 whenever the support 111 passes the table 110 it is stopped in register therewith, and when the receiving support 160 arrives at the position opposite the receiving table 168 at the left of Fig. 4, it is stopped in register 35 therewith. But immediately thereafter, the arm 162 strikes another fixed lug 169 and shifts the other holder 111 into line with the lifting devices. Meanwhile the carrier arm 170 takes the tumbler off support 160 at the 40 opposite side of the table, and shoves it across the table 168 by means of the reciprocating motion of a lever arm 171 engaging the sliding block 172 in the slotted table 173. The arm 171 is moved by a pin-and-slot en- 45 gagement with a disk 174 operated by gearing 175 from the power shaft 118. The lateral motion of the carrier arm 170, necessary to enable it to go behind the tumbler on the rest 160, is attained by pivoting on the block 50 172 a frame 176 immediately supporting the carrier arm 170, and this frame is swung on its pivot by engagement of roller stud 177 with a cam switch 178 on the table 173. The frame 176 is returned to normal position 55 by spring 179.

The mechanism for moving the article from off the loading table 110 and onto the rest 111 may consist of a slotted lever arm 107 reciprocated by a wrist-pin on a rotating 60 disk 108, and actuating a shove bar 109 pivoted thereto.

The operation of the device is as follows,—

A tumbler placed at one end of the loading table 110 is moved over onto the support 111 standing opposite such table, and 65

in front of the lifting box 131. The latter is then moved outwardly and upwardly by movement of rack 140 and it straddles over support 111, picks up the tumbler in the nest of revolving rollers 133, lifting it to a horizontal position, while the plug 142 is projected outward into the tumbler and immediately lifted by operation of rack 155 and places the tumbler in the glory hole 113. As it travels around with the furnace 112, it 70 is constantly rotated by the pinion 157 and its driving shaft 158 engaging the fixed rack and exposed on all sides to the flame. At the proper time, the tumbler is again lowered by the same agencies and deposited 80 on the rest 160 which has meantime been shifted into the relative position formerly occupied by the rest 111, through the agency of the shifting arms 162 moving sliding blocks 161 when struck by the fixed lugs 85 167. As the rest 160 with the tumbler comes opposite table 168, the rest and tumbler are stopped by the striking of arm 162 against lug 169 and thereupon the carrier arm 170 90 shoves the tumbler across the table 168.

What is claimed is,—

1. In a machine for treating glass articles, the combination with a continuously traveling article handling mechanism, of a fixed station, a transfer mechanism movable with and in respect to the article-handling mechanism, and means for moving the transfer mechanism to and holding it at the fixed station and moving it with the article-handling mechanism and in co-operative relation therewith, and means for effecting a transfer of articles between the transfer mechanism and the station while the transfer mechanism is stationary. 95

2. In a machine for treating glass articles, the combination of a continuously traveling article-handling mechanism, a fixed article handling mechanism, a transfer mechanism operatively interposed between the said handling mechanisms, and means 100 for positioning the transfer mechanism in co-operative relation with the fixed handling mechanism and for maintaining it in that position and for causing it to assume a co-operative relation with the movable handling mechanism and for maintaining it in that relation during a part of the movement of the latter. 110

3. In a machine for treating glass articles, the combination with a continuously traveling article handling mechanism, a transfer mechanism movable in respect to the handling mechanism in the direction of and contrary to the movement thereof, a non-traveling article handling mechanism, 120 and means whereby the transfer mechanism is moved relatively to the movable handling mechanism to alternately place it in co-operative relation therewith, and is moved with the movable handling mechanism to 125 130

maintain it in such relation and is arrested to hold it in coöperative relation with the fixed handling mechanism.

4. In a machine for treating glass articles, the combination with a continuously traveling article handler, of a fixed receiver station, a transfer mechanism movable in a closed path adjacent to the path of the handler operatively interposed between the handle and station, non-traveling means located at the receiver station adjacent to the path of the transfer mechanism to take articles therefrom, and means for moving the transfer mechanism into coöperative relation with the handler, and in coöperative relation therewith, and for temporarily retaining and arresting it in stationary coöperative relation with the non-handling means.
5. In a machine for treating glass articles, the combination of article-handling mechanism continuously traveling in a closed path around a central axis, a mechanism for delivering glass articles thereto, a transfer mechanism movable in a closed path around the central axis, and means for intermittently moving the transfer mechanism around such axis in coöperative relation with the article-handling mechanism during a part of the movement of the latter, and for arresting it in coöperative relation with the transfer mechanism.
6. In a machine for treating glass articles, the combination with a continuously traveling article handler, of a fixed loading and a fixed unloading station, a transfer mechanism movable in a closed path adjacent to the path of the handler, and operatively interposed between the handler and the stations, non-traveling means located at the stations and adjacent to the path of the transfer mechanism to deliver articles thereto and take them therefrom, and means for moving the transfer mechanism into and in coöperative relation with the handler, and for temporarily arresting the transfer mechanism in stationary coöperative relation with the mechanism at the said station.
7. In a fire-polisher, the combination with a furnace, a glass traveling mechanism and a glass handling mechanism all mounted for continuous movement around a common center, a glass receiving and delivering transfer mechanism, means for intermittently moving the glass receiving and delivering transfer mechanism around the common center, at times synchronous with the other parts moving therearound, and at times with a speed in excess of the speed of movement of said other parts, and means for actuating the handling mechanism to take articles from and deliver articles to the receiving and delivering transfer mechanism when moving in unison therewith.
8. In a glass-working device, the combi-

nation of a glass-handling part, glass-receiving and delivering transfer mechanism, means for continuously moving the handling parts and intermittently arresting and moving the glass-receiving and delivering transfer mechanism around a common center at times synchronously, and at other times with a velocity of movement of the one greater than the other, and means for actuating the handling parts to take articles from the glass-receiving and delivering transfer mechanism and to deliver articles thereto when the parts are moving in synchronism.

9. In a machine for treating glass articles, the combination of article-handling mechanism, continuously traveling in a closed path around a central axis, a mechanism for delivering glass articles thereto, a mechanism for receiving articles from the glass-working mechanism, a transfer mechanism, comprising two elements, movable with and in relation to the working mechanism, and means for arresting the transfer mechanism with one of its elements in coöperative relation with the delivery mechanism, bringing such element in coöperative relation with the handling mechanism, and for advancing it with such element and in such coöperative relation therewith, and for then moving the transfer mechanism to bring and to maintain its other element into coöperative relation with the handling mechanism, and for then arresting it with such last named element in coöperative relation with the receiving mechanism.

10. In a fire-polisher, the combination of a furnace, having an opening, an article rest below the level of the furnace, article-lifting mechanism adapted to move past the rest and take an article therefrom, and lift the same, and a glass-carrying spindle adapted to be projected to enter the article lifted by the lifting mechanism, and to further lift the same into coöperative relation with the furnace opening.

11. In a fire-polisher, the combination of a furnace opening, a rest, a plurality of positively driven rollers adapted to move past the rest, and to take an article therefrom and lift it, and a glass-carrying spindle adapted to be projected to engage the article so lifted, and to further lift the same into coöperative relation with the furnace opening.

12. In a fire-polisher, the combination of a furnace opening, a rest adapted to hold an article open end up, a pivoted elevating member having a plurality of driven rollers adapted to pass on opposite sides of the rest and remove the article therefrom and lift it into a substantially horizontal position, and a glass-carrying spindle adapted to be projected into the horizontal article and to swing the same to a coöpera-

tive position in respect to the furnace opening, and inverted with respect to its position on the rest.

13. The combination of a pair of associated parts rotating about a common center, means located at a loading station adjacent to the path of movement of one of the parts for loading the same, means for effecting a transfer from such associated

part to the other operative upon a movement ¹⁰ of the first named part less than a complete rotation past the loading station, and means for unloading the other part upon a further movement thereof past the loading station.

CHARLES M. STEIMER,
*Administrator of the estate of Theodore C.
Steimer, deceased.*
